UNITED STATES PATENT OFFICE.

LEMUEL F. EDWARDS, OF CRAWFORD, GEORGIA.

CORN AND PEA PLANTER.

SPECIFICATION forming part of Letters Patent No. 355,009, dated December 28, 1886.

Application filed April 9, 1886. Serial No. 198,369. (No model.)

To all whom it may concern:

Be it known that I, LEMUEL F. EDWARDS, of Crawford, Oglethorpe county, State of Georgia, have invented certain new and useful Improvements in Corn and Pea Planters, 5 of which the following is a specification.

My invention relates to that class of planters in which a vertical seed-slide is operated by a connection to a drive-wheel; and it consists 10 in the construction and arrangement of parts, as hereinafter described, reference being had to the annexed drawings, in which—

Figure 1 represents a side elevation of the planter; Fig. 2, a cross-section on the line *xx* of Fig. 1; and Fig. 3, a detail view of the inner side of the seed-slide and hopper support, 15 forming one side of the hopper.

For simplicity and cheapness of construction I use an ordinary plow-beam, A, to which 20 I attach the planting mechanism so that the same may at any time be removed and the plow used in the usual manner; also by means of the same bolts that secure the handles B to the beam I fasten the covers C, which may 25 be of any ordinary or approved construction.

In front of the plow D, which acts as an 30 opener, I secure the drive-wheel E, which is provided with a crank-shaft, F, by means of a hanger, G, secured to and straddling the plow-beam, the depending arms of the said hanger forming at their lower ends journal-bearings 35 for the shaft F.

The hopper for the material to be planted 40 consists of an upright supporting-piece, H, constituting one side of the said hopper, and a shell, I, of metal or other suitable material secured to the supporting piece or side H, and preferably of semi-conical shape, so as to direct the contents of the hopper to the contracted space at the bottom thereof adjacent 45 to the seed-slide.

The supporting side H may be attached to 50 the beam in any suitable manner; but I prefer to use a bolt, as at K, to secure the said side to the beam, and also attach it to one of the handles, as at L.

The seed-slide M moves vertically in a guiding-groove, N, in the inner face of the side H of the hopper, and is provided with an inclined aperture, O, which forms a seed-cup. 55 The vertical movement to the said seed-slide is imparted by a short rock-shaft, P, extend-

ing through the side H near the upper front end and carrying arms R and S, one arm being on the inner end of the said shaft and extending through a staple or eye, T, on the slide, and the other arm being on the outer end of the said shaft and connected by a pitman, U, to the crank-shaft F, on which is carried the drive-wheel E. The revolution of the said 60 drive-wheel by means of the pitman U causes the shaft P to oscillate, and the said shaft P, by means of the arm R, extending through the eye T, imparts to the slide M a vertical reciprocation in the guiding-groove N. Leading 65 from the said groove N, through the side H of the hopper and to the tube V, secured to the exterior of said side H, and which delivers the seed to the ground, is an aperture or passage, W, inclined correspondingly to the passage or seed-cup O in the seed-slide. Secured to the interior of the side H, and extending laterally across the groove N, is a retaining-strip, Y, located to cover the seed-cup of the 70 slide when the said cup is coincident with the passage W in the side H. The seed-cup in the slide travels from the lowest point in the hopper upward to the passage W in the side H, through which the seed escapes and falls to the ground, and then the cup is returned to 75 the bottom of the hopper, and thus continues the operation of dropping the seed to the ground at intervals of greater or less duration, the length of the said intervals depending on the size of the drive-wheel. The seed-cup 80 being inclined will receive and retain the grain until it reaches the escape-passage, and the strip Y will prevent the escape of any seed not carried by the cup, will also prevent the cup from carrying more than a predetermined quantity of seed, and also acts as a retaining-strip for maintaining the seed-slide in 85 its guiding-groove. The tube V leads from the escape-passage in the hopper to a position to the rear of the opener, and drops the seed in 90 the furrow, or the tube may terminate in a shoe, whereby the seed may be planted at a suitable depth.

The planter is designed more especially for 95 corn and peas, but may be used for other grain or seed. Being of such construction that the planting mechanism is adaptable to an ordinary plow without impairing the utility of the said plow, the planter is of more economical

construction than those which require supporting-frames of special construction.

I do not claim, broadly, a seed-slide reciprocating in a substantially vertical direction, as I am aware that the same is not new; but my invention is distinguished from such a construction in that I provide a groove in one side of the hopper and seat the seed-slide therein, thus obviating the use of guides or of slides, which project into the hopper and prevent all the seed from reaching the seed-cup, more or less being retained by the corners of the projecting parts, while in my construction all the seed will gravitate to the seed-cup, and hence should I desire, after planting one kind of seed, to plant another kind, none of the first kind of seed would remain and mix with the latter kind.

While I do not claim, broadly, a drive-wheel and connections to a seed-slide, I have found the construction I employ to be simple and effective in connection with the slide I use.

Without limiting myself to the precise construction and arrangement of parts shown, I claim—

In a seed-planter, the combination, with a hopper having a vertical groove in one side, of a vertically-reciprocating seed-slide seated in said groove flush with the interior of the hopper, a rock shaft extending through one side of the hopper and carrying an arm at each end, the arm on the inner end being connected with the slide, a drive-wheel, and a pitman extending from said drive-wheel to the arm on the outer end of the said rock-shaft, substantially as described.

In testimony whereof I have signed my name to this specification in the presence of two subscribing witnesses.

LEMUEL F. EDWARDS.
